UNITED STATES PATENT OFFICE.

RALPH W. CRARY, OF WAUKESHA, WISCONSIN.

CAN.

1,308,891.

Specification of Letters Patent.

Patented July 8, 1919.

Application filed May 23, 1917. Serial No. 170,342.

To all whom it may concern:

Be it known that I, RALPH W. CRARY, a citizen of the United States, residing at Waukesha, in the county of Waukesha and 5 State of Wisconsin, have invented a new and useful Can, of which the following is a specification.

The object of my invention is to produce a simple and efficient sealing ring for that 10 type of cans comprising mating circumferential flanges of can body and cover.

The accompanying drawings illustrate my invention. Figure 1 is a perspective fragmentary view, illustrating my invention; 15 Fig. 2 a perspective view of the ring in one form in which it may be applied to the can; Fig. 3 a fragmentary section.

In the drawings, 10 indicates the main body of the can provided with a circumferential flange 11 at its end. Mating with the 20 open end of the body 10 is a cover 12, provided with a circumferential flange 13, the edge of which is turned backwardly, as indicated at 14.

25 Thus far the structure is common can and cover construction. My improved sealing strip comprises a ring having flanges 15 and 16 which may be either initially formed parallel with each other, as shown in Fig. 1, or 30 may be formed at right angles to each other, as shown in Fig. 2. The mating ends of the ring are formed with quite short overlapping tongues 15' and 16', so that they overlap above and below the flanges 10 and 13 35 for a short distance. By this arrangement,

the abutting ends of the ring are stepped relative to each other, and the projecting tongues being comparatively short, the overlapped stepped portions have sufficient rigidity to firmly hold the overlaid portions of 40 the can flange and cap flange, respectively. The ring is either slipped endwise upon the flanges, if of the initial form shown in Fig. 2, or wrapped around the edges of the flanges if of the initial form shown in Fig. 45 1. If of the form shown in Fig. 2, flange 16 is then rolled beneath flange 11 of the can, and in either case the two flanges 15 and 16 are rolled tightly upon the flanges 10 and 13, the inner edge of flange 15 being down-turned over the inner edge of the portion 14, thus firmly clamping the cover upon the can.

I claim as my invention:

The combination with a can and cover 55 having mating circumferential flanges, of a sealing ring applied to said circumferential flanges, said sealing ring comprising a strip of material having substantially parallel flanges embracing the circumferential flanges 60 of the can and cover and having abutting ends in the form of short fingers which are stepped and disposed in abutting relation, one contacting the flange of the cap and the other contacting the flange of the can. 65

In witness whereof, I have hereunto set my hand at Waukesha, Wisconsin, this seventeenth day of May, A. D. one thousand nine hundred and seventeen.

RALPH W. CRARY.
